FUNCTION GENERATING CIRCUITS REQUIRING ONLY LINEAR ELEMENTS

Brooks Ehrmon Cowart, Pacoima, Lloyd David Ball, Los Angeles, George Bruer Crane, Redondo Beach, and Orin Henry Knowlton, Jr., Los Angeles, Calif., assignors to Gilfillan Bros. Inc., Los Angeles, Calif., a corporation of California

Filed Mar. 14, 1955, Ser. No. 494,178

1 Claim. (Cl. 235—197)

This invention relates to function generating circuits requiring only linear elements and, more particularly, to such circuits for generating time-varying signals representing such functions as: hyperbolas; parabolas; and ellipses, only linear circuit elements being required, where these elements may also be of a passive nature such as inductors, capacitors, or resistors.

Many types of function generators for providing time varying functions are presently available in the art, where nonlinear elements are employed. For example, diode limiter circuits may be utilized to provide a time varying output voltage X_o which varies in accordance with a time varying input voltage X_1 , in a specified manner; the diode characteristic being selected to provide the desired functional transition from the input signal X_1 to the output signal X_o . Suitable circuits of this type, for example, are shown on pages 273 through 278 of a book entitled "Electronic Analog Computers" by Korn and Korn published in 1952 by the McGraw-Hill Book Company, New York, Toronto and London.

Many other nonlinear elements have been employed such as, for example, thyrites and ferrites. Moreover, vacuum tubes have been utilized to provide logarithmic functions by biasing the tube at a nonlinear characteristic portion which approximates the desired function.

It is apparent that in utilizing nonlinear elements to provide a desired time varying function, considerable care must be exercised to obtain specific characteristics. As a result the elements specified are necessarily costly since they must conform with particular specifications. Furthermore, such carefully selected nonlinear elements may vary in characteristics due to changes in operating conditions such as temperature or pressure. Thus an accurate function generator employing such elements not only has an added cost factor due to the special characteristics required but also must include means for regulating such operating conditions as temperature and pressure to within certain prescribed boundaries.

A further limitation inherent in the prior art practice is the fact that frequently the nonlinear element required must be a vacuum tube or other active element, where the term active is utilized to indicate that the element requires activating power in order for it to function. As a result such circuits require power to maintain the nonlinear elements in the proper operating position and are also subject to inaccuracies due to variation in the power supply utilized.

Furthermore, it is apparent that such active elements cost considerably more than passive elements such as resistors and capacitors, for the same degree of accuracy.

The present invention obviates the above and other disadvantages inherent in the prior art by providing a class of function generating circuits utilizing linear elements, which may all be of a passive nature. According to the basic concept of the invention, the particular function to be generated is first translated into a sum of exponential functions where the exponential functions

2

may be delayed in time according to a predetermined initial condition of the function desired.

A large class of time-varying functions may be simulated in this manner, where the degree of accuracy inherent in the simulation is a function of the number of linear elements employed providing a corresponding number of exponential variables. The basic technique of the invention, for example, may be utilized to simulate a time-varying hyperbolic function such as: $y=c/t$. Since the simulating exponential functions cannot provide an initial condition of $y=\infty$, the simulation process must begin after a predetermined initial time interval which may be designated as t_i . This hyperbolic function then may be approximated with a reasonable accuracy by the combination of two exponential functions as follows:

$$Ae^{k_1(t-t_i)} + Be^{k_2(t-t_i)} \approx \frac{c}{t}$$

where $t \geq t_i$ for accurate simulation.

The constants A and B and the exponent factors k_1 and k_2 may be determined by selecting points in the hyperbola through which the simulating function is to pass, or by selecting slopes and points which may best be approximated by the exponentials. The initial portion of the hyperbola, for example, has a sharply negative slope and therefore may be most accurately simulated by an exponential having a large negative exponential factor k_1 . The ending portion of the hyperbola, on the other hand, has a small negative slope and therefore may be most accurately simulated by an exponential having a small exponential factor k_2 .

In this manner any function may be simulated by combining a plurality of exponentials, where the accuracy inherent in the simulation is a function of the number of points that the exponentials are selected to pass through. The second basic step of the invention is to select a set of linear elements, which may all be passive, to provide the basic exponential functions required. Where two exponentials are specified, for example, two circuits including resistance and capacitance elements may be utilized or two equivalent circuits including resistance and inductance elements.

After establishing the basic configuration of linear circuit elements which may provide the simulating exponentials, the transformation function for the simulating circuit arrangement is formulated. This transformation or transfer function may be obtained by well-known Laplace transform operational calculus.

The transformed function is then converted into a time-varying function where the coefficients and initial conditions specifying the function remain as unknowns in terms of the linear circuit elements employed. Suitable values for these linear circuit elements are then determined by a simultaneous equation solution where the coefficients of the desired simulating exponential function series are compared with the unknown coefficients of the time varying function.

Many other time varying functions may be generated in this manner. A parabolic function, for example, may be generated through a combination of increasing exponential circuits where an initial shift in time may be introduced corresponding to the $y=0$ portion of the parabola. It should also be understood that although the actual circuit must function in a time domain, the time variable may nevertheless be considered to represent other independent variables. Thus the function $y=f(x)$ may be represented where x is considered to be equivalent to the independent variable of time.

Accordingly, it is an object of the present invention to provide a class of function generating circuits which utilize only linear elements.

Another object of the invention is to provide a linear

element circuit for function generating obviating the necessity of nonlinear elements requiring special characteristics and accurately regulated temperature and pressure conditions.

A further object is to provide a class of function generating circuits which may utilize passive elements obviating the necessity for active elements providing the desired function which require power for activation, the power being necessarily accurately regulated to provide the desired function.

Still another object of the invention is to provide a function generator which may utilize passive elements avoiding the inaccuracies resulting in operation where a well regulated power supply is required for activating active elements.

Yet a further object is to provide an economical class of function generating circuits where special nonlinear elements are not required nor particular operating conditions such as temperature or pressure.

A more specific object of the invention is to provide a class of function generating circuits where a desired function is simulated by exponential functions, each exponential function being provided by a corresponding set of linear elements which may be passive elements such as inductors, capacitors or resistors.

The novel features which are believed to be characteristic of the invention, both as to its organization and method of operation, together with further objects and advantages thereof, will be better understood from the following description considered in connection with the accompanying drawings. It is to be expressly understood, however, that the drawings are for the purpose of illustration and description only, and are not intended as a definition of the limits of the invention.

Fig. 1 is a block diagram of a basic embodiment of the invention;

Fig. 2 is a schematic diagram of one species of the invention for providing a signal simulating a rectangular hyperbolic function;

Fig. 2a is a graph indicating the correspondence between the hyperbolic function to be simulated and the exponential functions utilized according to the present invention; and

Fig. 2b is an equivalent circuit for the embodiment of Fig. 2.

Reference is now made to Fig. 1 wherein the basic embodiment of the invention is illustrated in block diagram form. As indicated in Fig. 1 the basic embodiment comprises a plurality of exponential circuits indicated as providing the functions:

$$Ae^{k_1(t-t_1)}; Be^{k_2(t-t_2)}; \dots Ne^{k_n(t-t_n)}$$

Each of the exponential circuits receives certain initial amplitude conditions, represented by corresponding signals, and also initial time conditions in order to establish initial starting points for function simulation. The initial starting points may be generated as time delays or may be assumed to exist as unused portions of the signal generated. In other words, the time variable t_1 may represent either an actual time delay before initiating the exponential function or the time interval of the unused portion.

The particular significance of Fig. 1 may best be understood by considering a specific mechanization as illustrated in Fig. 2 where a signal is provided simulating the rectangular hyperbolic function

$$y = \frac{175}{t}$$

in the interval 5 sec. $\leq t \leq 50$ sec.

Since many curve fitting techniques may be utilized to approximate this function in the interval between $t=5$ and $t=50$, it is not deemed necessary to show the specific

manner of deriving a simulating function. A suitable function is found to be:

$$65(.136e^{-t/62.1} + .864e^{-t/5.95}) \approx \frac{175}{t}$$

It will be noted that this function is expressed in a form where the initial time condition $t_1=5$ is effectively provided by failing to utilize the first 5-second portion of the function which starts from an amplitude 65. This function may also be expressed as follows:

$$35(.136e^{-(t-5)/62.1} + .864e^{-(t-5)/5.95}) \approx 175/t$$

where $t \geq 5$ for simulation. This function may be achieved by introducing an actual time delay in initiating the operation of the exponential circuits.

This exponential simulating function may be provided by the double RC exponential circuit shown in Fig. 2.

Referring now to Fig. 2, it is noted that the embodiment includes a first RC exponential circuit including a capacitor C_1 and a resistor R_1 . The capacitor C_1 is initially charged to the voltage E applied thereto through normally closed relay contact R_{t_0-1} forming part of a relay R_{t_0} .

An output signal is derived from the junction of C_1 and R_1 and is applied to a second RC exponential circuit, including resistor R_2 and capacitor C_2 , having one end connected to resistor R_2 and the other end connected to ground. Capacitor C_2 receives an initial charging voltage of 0 volt through a normally closed second contact R_{t_0-2} of relay R_{t_0} . It will also be noted that a second relay R_{t_x} is included, having a normally closed contact $R_{t_{x-1}}$ completing connection between capacitor C_1 and resistor R_1 in the first exponential circuit. When relay R_{t_x} is actuated, contact $R_{t_{x-1}}$ is transferred to an output lead so that the signal may be read across capacitor C_1 at any time, designated as t_x . In the general operation of the embodiment of Fig. 2 relays R_{t_0} and R_{t_x} are normally unactuated and the associated contacts therewith are in the position shown in Fig. 2. During the pre-operation period capacitor C_1 is charged to the potential E and capacitor C_2 is discharged to ground potential. It will be understood that the particular potentials illustrated in Fig. 2 are by no means intended as a limitation of the invention.

The operation of the circuit begins at time t_0 when relay R_{t_0} is actuated opening associated contacts R_{t_0-1} and R_{t_0-2} . In the particular operation to be discussed below, it will be assumed that potential E is 65 volts and that at time t_0 occurs at zero time as indicated in Fig. 2a. It will be understood, however, that other suitable times t_0 may be selected such as $t_0=10$ seconds at which time the potential across capacitor C_1 should be selected to be 17.5 volts as indicated in Fig. 2a. The time condition t_0 then, corresponds to the general condition t_1 indicated in Fig. 1 and discussed above as covering any of the possible initial time conditions.

After signal t_0 actuates relay R_{t_0} , opening the associated contacts, capacitor C_1 begins to discharge through the parallel path of the exponential circuit including the resistor R_2 and capacitor C_2 coupled in series and through resistor R_1 . It will be shown in the detailed discussion which follows that the values of the components of these exponential circuits may be selected to simulate the desired hyperbolic function with a high degree of accuracy during a considerable portion of the time interval. Thus, in Fig. 2a, it will be noted that the function $y=175/t$ is accurately simulated by the summation of two exponentials: $y=56.16e^{-t/62.1}$ and $y=8.84e^{-t/5.95}$ in the interval starting from t approximately equal to 8 seconds through the time $t=60$ seconds.

In view of the continuous computation of the time varying function according the invention, the desired final time condition may be selected at any point following the first point of reasonable accuracy. Thus, relay R_{t_x} may be actuated at any time following to equal to approximately 8 second, transferring contact $R_{t_{x-1}}$ to provide

an output signal indication for the value of the function at that time.

A more detailed explanation of a particular operation of the invention as employed in an initial velocity computing circuit is found in copending application "Variable Range Signal Generating Circuit With Means for Computing Initial Velocity" by Lloyd David Ball et al., filed March 7, 1955, Serial No. 492,482, now Patent No. 2,832,537; and "Velocity Tracking System For Increasing The Range of Acquisition of Moving Targets" by Ball et al., filed March 7, 1955, Serial No. 492,627. The present invention is shown in means 200 of Fig. 2 in the

The Kirchoff law equations for the equivalent circuit shown in Fig. 2b may be expressed as follows:

$$i_1.R_2+1/C_1.i_1.dt+E+1/C_2.i_1.dt-(i_2.R_2+1/C_2.i_2.dt)=0$$

$$i_1.R_2+1/C_2.i_1.dt-(i_2.R_1+i_2.R_2+1/C_2.i_2.dt)=0$$

These equations may then be transformed according to Laplace transform operational calculus as follows:

$$T(i_1).(R_2+1/SC_1+1/SC_2)-T(i_2).(R_2+1/SC_2)=-E/S$$

$$T(i_1).(R_2+1/SC_2)-T(i_2).(R_1+R_2+1/SC_2)=0$$

The transform of i_2 is then found to be:

$$T(i_2)=\frac{(R_2+1/SC_1+1/SC_2)}{(R_2+1/SC_2)}\frac{E/S}{0}$$

$$=\frac{(R_2+1/SC_1+1/SC_2)}{(R_2+1/SC_2)}\frac{-(R_2+1/SC_2)}{-(R_1+R_2+1/SC_2)}$$

$$=\frac{-E/S.(R_2+1/SC_2)}{-\{(R_2+1/SC_2)+1/SC_1\}[(R_2+1/SC_2)+R_1]-(R_2+1/SC_2)^2\}}$$

$$=\frac{E/S.(R_2+1/SC_2)}{(R_2+1/SC_2).(R_1+1/SC_1)+R_1/SC_1}\times\frac{S^2/R_1.R_2}{S^2/R_1.R_2}$$

$$=\frac{E/R_1.(S+1/R_2.C_2)}{S^2+S(1/R_1.C_1+1/R_2.C_2+1/R_2.C_1)+1/R_1.C_1.R_2.C_2}$$

range signal generating circuit application, Serial No. 492,482 and in Fig. 6 in means 610 of the velocity tracking system covered in application Serial No. 492,627. In these applications, the present invention is employed to compute initial velocity and is actuated at time t_0 to generate a hyperbolically varying signal defined as

$$\frac{\Delta d}{\Delta t}$$

where Δd is the range difference between two points through which a target passes over the time interval Δt .

In employing the present invention in the above particular application, relays Rt_0 are actuated at the time the target whose initial velocity is to be computed passes a first range point. The circuit values of the hyperbolic function generating circuit of the invention are selected so that the output signal at all times represents

$$\frac{\Delta d}{t-t_0}$$

Thus, as soon as the target is detected passing through a known range difference point constituting the factor Δd relay Rt_x of the present disclosure is actuated so that the output signal is directly equal to

$$\frac{\Delta d}{t_x-t_0}$$

where t_x-t_0 is equal to Δt .

In this manner the invention provides a simple means of continuously generating a variable signal representing the initial velocity of a target according to a hyperbolic function so that the instant the target passes through a second known range point an accurate signal may be read out.

In each of the above-identified applications, it will be noted that the capacitor C_1 is also employed as a feedback device for a chopper-stabilizer D.C. amplifier. In this manner, not only is the initial velocity computation performed in accordance with the desired hyperbolic function provided by the present invention, but also the final signal developed across capacitor C_1 is incorporated into the integrating feedback path as an initial condition for a subsequent integration to form a varying velocity signal.

The equivalent circuit for the embodiment of Fig. 2 is shown in Fig. 2b, where it is assumed that the relay Rt_0 is actuated, initiating the hyperbolic function generating operation, and that relay Rt_x has not been actuated.

The transform for the voltage ec_1 across C_1 may then be expressed as follows:

$$T(ec_1)=T(i_2).R_1$$

$$=\frac{E.(S+a)}{S^2+bS+c}=\frac{E(S+a)}{(S-k_1).(S-k_2)}$$

where:

$$a=1/R_2.C_2$$

$$b=1/R_1.C_1+1/R_2.C_2+1/R_2.C_1(k_1+k_2)$$

$$c=1/R_1.C_1.R_2.C_2$$

and k_1 and k_2 are the roots of $S^2+bS+c=0$.

The transform $T(ec_1)$ may then be expressed in partial fractions:

$$T(ec_1)=E\left[\frac{k_1+a}{k_1-k_2}\frac{1}{S-k_1}+\frac{k_2+a}{k_2-k_1}\frac{1}{S-k_2}\right]$$

Performing the inverse transform the general form of time function is found to be:

$$ec_1(t)=E\left[\frac{k_1+a}{k_1-k_2}e^{k_1 t}-\frac{k_2+a}{k_1+k_2}e^{k_2 t}\right]$$

Suitable circuit constants may then be determined by comparing the simulating function desired with this general time function; for example:

$$k_1=-1/62.1$$

$$k_2=-1/5.95$$

$$\frac{k_1+a}{k_1-k_2}=.136$$

$$a=1/R_2.C_2=.136\left(\frac{1}{5.95}-\frac{1}{62.1}\right)+\frac{1}{62.1}$$

$$b=\frac{1}{R_2.C_2}+\frac{1}{R_1.C_1}+\frac{1}{R_2.C_1}=\frac{1}{62.1}+\frac{1}{5.95}$$

$$c=\frac{1}{R_1.C_1.R_2.C_2}=\frac{1}{5.95}\frac{1}{62.1}$$

It will be noted that, since only three equations are provided and there are four unknowns in terms of circuit elements, the solution which is satisfactory is not unique. Therefore, although precise solutions may be determined mathematically, it is considered satisfactory for the purpose of the invention to establish the basic configuration of elements and to approximate reasonable circuit values therefor, precise values being then determined experi-

mentally by noting the simulating function which results. The following circuit element values have been found satisfactory for providing the simulating exponential functions above:

$R_1=6.8$ megohms

$C_1=2$ microfarads

$R_2=6.8$ megohms

$C_2=4$ microfarads

The general technique of derivation in accordance with the present invention may now be summarized as follows.

(1) The function to be simulated as a continuous time function is approximated by series of exponential which may be expressed as follows:

$$E \cong A e^{k_1(t-t_0)} + B e^{k_2(t-t_0)} = \dots N e^{k_n(t-t_0)}$$

(2) A plurality of sets of linear elements are then provided, one set being included for each of the terms in the exponential series.

(3) The basic circuit configuration is then transformed in terms of unknown element values to provide the transformation function:

$$T(Eo) = \frac{\Delta U(s)}{\Delta L(s)}$$

where $T(Eo)$ represents the transformed output signal, $\Delta U(s)$ represents the upper term in the transformation function and $\Delta L(s)$ represents the lower term, or root function which is equated to zero to determine the roots k_1 and k_2 , etc. In the example above:

$$\Delta U(s) = E(s+a)$$

$$\Delta L(s) = s^2 + bs + c = (s - k_1)(s - k_2)$$

where

$$a = 1/R_2 C_2$$

$$b = 1/R_1 C_1 + 1/R_2 C_2 + 1/R_2 C_1$$

$$c = 1/R_1 C_1 R_2 C_2$$

(4) The transformed function $T(Eo)$ is then rewritten in the form:

$$T(Eo) = \frac{\Delta U(k_1)}{\Delta L'(k_1)} \cdot \frac{1}{s - k_1} + \frac{\Delta U(k_2)}{\Delta L'(k_2)} \cdot \frac{1}{s - k_2} + \dots + \frac{\Delta U(k_n)}{\Delta L'(k_n)} \cdot \frac{1}{s - k_n} \quad 40$$

which may be expressed as the time function:

$$Eo(t) = \frac{\Delta U(k_1)}{\Delta L'(k_1)} \cdot e^{k_1 t} + \frac{\Delta U(k_2)}{\Delta L'(k_2)} \cdot e^{k_2 t} + \dots + \frac{\Delta U(k_n)}{\Delta L'(k_n)} \cdot e^{k_n t}$$

The terms $\Delta L'(k_1)$ and $\Delta L'(k_2)$ are derivatives of $\Delta L(s)$ evaluated at the roots k_1 and k_2 , respectively. In the above example, $\Delta L'(s) = 2s + b$ where $b = -(k_1 + k_2)$. Thus,

$$\Delta L'(k_1) = 2k_1 - (k_1 + k_2) = k_1 - k_2$$

$$\Delta L'(k_2) = 2k_2 - (k_1 + k_2) = k_2 - k_1$$

(5) Finally the values of the various circuit constants are obtained by equating the unknown coefficients A and B, etc., to the corresponding terms derived from the transformation providing the relationship:

5

$$A = \frac{\Delta U(k_1)}{\Delta L'(k_1)} ; B = \frac{\Delta U(k_2)}{\Delta L'(k_2)} \dots ; N = \frac{\Delta U(k_n)}{\Delta L'(k_n)}$$

From the foregoing description, it is apparent that the present invention provides a class of functioning generating circuits requiring only linear elements, where these elements may also be of a passive nature such as inductors, capacitors and resistors.

While the invention has been specifically illustrated with respect to a resistor-capacitor exponential circuit, it will be understood that other exponential circuits may be utilized. Furthermore, it may be understood that, while the specific example illustrated relates to simulation of a hyperbola, other functions such as parabolas and ellipses may be simulated.

20 What is claimed is:

A hyperbolic function generator comprising: a first circuit including direct-current source of potential, a switch, and a resistor connected in series; a second circuit including a first capacitor connected in parallel with said resistor; a third circuit including a resistor and a second capacitor connected in series, said third circuit also being connected in parallel with said resistor; a switch connected in parallel with said second capacitor; and means for opening said switches simultaneously.
